(57) **CLAIM**

The ornamental design for a tobacco wrapper, as shown and described.

DESCRIPTION

FIG. 1 is a perspective view of a tobacco wrapper showing my new design;

FIG. 2 is a front elevational view thereof, wherein the rear elevational view is a mirror image thereof;

FIG. 3 is a left side elevational view thereof,

FIG. 4 is a right side elevational view thereof;

FIG. 5 is a top plan view thereof;

FIG. 6 is a bottom plan view thereof; and,

FIG. 7 is a perspective view of tabacco wrapper, the broken lines shown are for illustrative purposes only and form no part of the claimed design.
